(57) **CLAIM**

The ornamental design for a fluid coupling, as shown and described.

DESCRIPTION

FIG. 1 is a perspective view of a fluid coupling showing our new design.

FIG. 2 is a first end view of the fluid coupling.

FIG. 3 is a second end view of the fluid coupling.

FIG. 4 is a first side view of the fluid coupling.

FIG. 5 is a second side view of the fluid coupling.

FIG. 6 is a top view of the fluid coupling; and,

FIG. 7 is a bottom view of the fluid coupling.

The broken lines represent portions of the fluid coupling that form no part of the claimed design.
